(57) **CLAIM**

The ornamental design for a chair caddy, as shown and described.

DESCRIPTION

FIG. 1 is a perspective view of a chair caddy according to my new design.

FIG. 2 is a right side view of the chair caddy as in FIG. 1.

FIG. 3 is a front view of the chair caddy as in FIGS. 1-2.

FIG. 4 is a rear view of the chair caddy as in FIGS. 1-3.

FIG. 5 is a bottom view of the chair caddy as in FIGS. 1-4; and,

FIG. 6 is a top view of the chair caddy as in FIGS. 1-5.

The features shown in broken lines in the Figures indicate stitching that forms part of the claimed design.
